SMOKING PIPE

Cal V. Brown, Richmond, Calif.

Application August 23, 1944, Serial No. 551,500

2 Claims. (Cl. 131—192)

1

This invention relates to improvements in tobacco pipes and has particular reference to the construction of the stem portion thereof.

The principal object of the invention is the provision of a tobacco pipe stem so devised that the stem may be readily folded or nested over the top of the pipe bowl, thus providing a compact pipe arrangement that can be readily carried by the user, with the pipe occupying but a minimum amount of space in the user's pocket.

A further object of the invention is to provide a jointed pipe stem that can be easily cleaned, thus rendering the same highly sanitary.

Another object of the invention is to produce a smoking pipe of the character described that is simple in construction, strong and durable, yet light in weight, and unusually compact and highly efficient in use.

All of the aforementioned and still other objects and advantages of my invention will become apparent from a study of the following specifications, taken with the accompanying drawing where like characters of reference designate corresponding parts throughout the several views.

Fig. 1 is a longitudinal side elevational view of one type of smoking pipe embodying the invention;

Fig. 2 is a central, vertical, longitudinal, sectional view of the smoking pipe;

Fig. 3 is an exploded, sectional, horizontal view of a pair of members that form one of the jointed portions of the pipe;

Fig. 4 is an especially constructed bolt and nut employed for hingedly securing the jointed portions together;

Fig. 5 is a top plan view of a pair of members that form one of the jointed portions of the pipe;

Fig. 6 is a side elevational view of the pipe, showing the stem in folded position;

Fig. 7 is a detail view in elevation of one of the halves that forms a jointed portion;

Fig. 8 is a view in perspective of the pair of members of Figs 3 and 5, as assembled.

Referring in detail to the drawings the numeral 9 designates the bowl of an ordinary pipe and the numerals 10 designate a bolt having a slotted head 11, said bolt serving to retain the hinged sections of the pipe stem together. The numeral 12 designates a female spacer coupling member that is interposed between the jointed members 14, said jointed members, spacer and mouth piece 13 having a smoke passageway 15 that leads from the bowl. The jointed members 14 are constructed of mating halves 14' and 14'' as illustrated in Figs. 3 and 5, each half being formed with a hole 16 that is provided to accommodate the bolt 10 which functions to hingedly secure the halves together. Each of the halves 14' and 14'' forming the jointed member 14 is formed at one side with an extension 19, which is substantially semi-circular in cross section and is provided with a flat inner face 22. The other side of the extension 19 is cut away to provide a concave face 23 which merges at its lower end into a relatively thin stop wall 21. The concave faces 23 of each of the halves interfit with and act as bearing surfaces for the respective extensions 19, during the pivotal folding movement of the parts. The numerals 17 designate male portions that are formed on each end of the jointed members 14 and which are capable of extending into female portions formed into the bowl piece 9, coupling member 12 and mouth piece 13 whereby the various parts forming the pipe and stem are removably secured together. The numeral 18 designates the inner portion of the bowl 9, the smoke passageway 15 leading therefrom through the jointed members and around the bolts 10, each bolt having a threaded nut 24 for holding it in position. The number 20 designates a 45° bevel surface on the member 14 and the number 21 an extension thereon. When it is desired to fold the pipe, it is apparent that the stem 13 and coupling member 12 will be turned upwardly so that the stem will closely overlie and be substantially parallel to the top face of the bowl 9. During this pivotal movement of the stem and coupling members, the extensions 19 of the halves 14' and 14'' will slide over the respective concave bearing surfaces 23, and, at the completion of the folding, the bevelled faces 20 on the upper ends of the halves 14' and 14'' will abut one another, as best shown in Figure 6.

From the foregoing description taken in conjunction with the accompanying drawings it will be apparent that the invention possesses certain unique features of construction, whereby the various parts forming the stem are removably and hingedly secured together in a manner which facilitates the proper cleaning thereof and enables the stem portion to be folded around the bowl portion into a compact form requiring the minimum of space for carrying.

It is to be understood that the form of the invention herewith shown and described is to be taken as a preferred example of the same and that changes relative to the material, size, shape and arrangement of parts can be resorted to

2

without departing from the spirit of the invention or the scope of the subjoined claims.

Having thus described my invention, I claim:

1. A smoking pipe embodying in its construction a bowl portion and a stem portion, the stem portion comprising a pair of jointed members adaptable for pivotal movement, an intermediate spacing member, and a mouth piece, the jointed members being formed with opposed male end portions and the intermediate spacing member with oppositely opposed female end portions whereby the jointed members are removably secured together, the spacer member being of such length relative to the height of the pipe bowl as will enable the stem to be folded at right angles and a portion thereof extend in parallelism over and in proximity to the top face of the bowl.

2. A smoking pipe embodying in its construction a bowl portion and a stem portion removably secured thereto, the stem portion comprising a pair of jointed members, an intermediate spacing member and a mouth piece removably secured to one of the jointed members, each jointed member being in two parts, said parts comprising mat-

ing extensions and bearing surfaces for interfitting said parts, a pin for hingedly securing each pair of halves together, each half having a male end portion, the intermediate spacing member being formed with opposed female end portions whereby the jointed members are removably secured together, the intermediate spacing member being of such length relative to the height of the pipe bowl as will enable the stem to be folded at right angles and the mouth piece thereof extend in parallelism over and in proximity to the top face of the bowl.
